UNITED STATES PATENT OFFICE.

FRANK JOSEPH DAVIS, OF SAN FRANCISCO, CALIFORNIA, ASSIGNOR TO BETHLEHEM SHIPBUILDING CORPORATION, LTD., OF BETHLEHEM, PENNSYLVANIA, A CORPORATION OF PENNSYLVANIA.

TAKE-UP DEVICE FOR ENGINE-ROOM TELEGRAPHS.

1,307,727.

Specification of Letters Patent. Patented June 24, 1919.

Application filed January 4, 1919. Serial No. 269,641.

To all whom it may concern:

Be it known that I, FRANK JOSEPH DAVIS, a citizen of the United States, residing in the city and county of San Francisco, State of California, have invented a new and useful Take-Up Device for Engine-Room Telegraphs, of which the following is a specification.

My invention relates to a novel construction of a take-up device for engine room telegraphs, wherein I employ or locate in the engine room, a back plate or guide plate, which is fixed or fastened stationary in the desired location on a bulkhead, stiffener or the like in the engine room by suitable brackets or the like, said back plate supporting a front plate or sliding plate, which is vertically movable or adjustably supported with respect to or upon said back plate, the engine room telegraph receiver being fastened to said front plate, which may be considered as a unit with said receiver, said plates carrying abutments on their upper portions with which I collocate a novel and simple arrangement of tension devices, whereby a constant tension is at all times maintained upon the wires leading from the bridge to the engine room, which is essential for the correct operation of the telegraph instruments, means being provided so that in case the distance between the telegraph stand on the bridge and the receiver in the engine room should change, due to expansion or movement of the vessel, or for any other reason, my novel device will compensate for this movement or change of distance through the medium of said tension devices and sliding plate employed and their adjuncts and thereby maintain a constant tension on the whole system, and further any desired tension on the telegraph wires can be readily obtained by adjusting the springs or tension devices.

To the above ends, my invention consists of a novel construction of a take-up device for engine room telegraphs, the novel features of which will be hereinafter fully set forth, and pointed out in the claims appended hereto.

For the purpose of illustrating my invention, I have shown in the accompanying drawings one form thereof which is at pres-

ent preferred by me, since the same will be found in practice to give satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a front elevation of the sliding plate, guide plate, tension devices and their adjuncts of a take-up device for engine room telegraphs, embodying my invention, the telegraph receiver being omitted therefrom.

Fig. 2 represents a side view of Fig. 1, but showing the telegraph receiver thereon.

Fig. 3 represents a section on line 3—3 Fig. 1.

Fig. 4 represents a diagrammatic view of the bridge, engine room, the connections therebetween and their adjuncts to which my invention is especially applicable.

Similar numerals of reference indicate corresponding parts in the figures.

Referring to the drawings:—

1 designates the front plate or sliding plate of my novel take-up device for engine room telegraphs, and

2 designates the back plate or guide plate which is fixed or fastened stationary in the desired location in the engine room, as on a bulkhead or stiffener or the like by the necessary brackets or the like to suit the circumstances.

I provide vertical guide ways 3 on the back of the front plate 1, which can be formed in any suitable or convenient manner, being constructed in the present instance by the vertical strips 4 having the plates 5 secured thereto by the bolts or studs 6, whereby vertical ways 3 are formed between the plates 5 and 1, which receive the vertical opposite edges of the fixed or stationary back plate 2.

Near the top of the front or sliding plate 1, I locate the brackets or angles 7 which are preferably two in number, having the vertical member 8, which is fastened to the top of the front plate, by means of suitable fastening devices 9, while the horizontal members 10 of said brackets have the holes 11

therethrough, through which freely pass the rods 12, the upper ends of said rods being threaded, as indicated at 13, and passing through the horizontal member 14 of the 5 brackets or angles 15, whose vertical member 16 is secured to the top of the back or guide plate 2 by means of the bolts, studs or other fastening devices 17. It will be seen that the horizontal members 10 and 14 form 10 abutments for coaction with the tension devices to be referred to.

18 and 19 designate lock nuts, which are located respectively above and below the horizontal flange or abutment 14, whereby 15 each rod 12 is secured in fixed position with respect thereto, but can be adjusted vertically if desired by manipulating said lock nuts.

20 designates coil springs or tension devices, whose lower ends rest upon the cup-shaped washers 21 and their upper ends upon washers 22, above which are located the adjusting nuts 23 and the lock nuts 24.

It will thus be seen from the foregoing 25 that the upper ends of the rods 12 are secured in fixed relation with respect to the brackets or angles 15, but can be adjusted vertically when desired by manipulating the lock nuts 18 and 19, so that said brackets 30 15 and back or guide plate 2 are stationary as a unit, but that the front or sliding plate 1 and its brackets 8 may have a cushioned up and down movement with respect to the fixed back plate 2, the extent of said movement being determined by the tension of the springs 20, which can be readily adjusted 35 to the desired extent by manipulating the nuts 23, after which the lock nuts 24 lock said nuts 23 in the desired position, so that 40 the extent of vertical movement of the front plate 1 and its adjuncts with respect to the fixed plate 2 can be regulated, according to requirements.

25 designates an engine room telegraph 45 receiver, which is fastened to the lower portion of the front or sliding plate 1, which latter moves in unison with the receiver and may be considered as a unit with said receiver.

50 The engine room telegraph receiver 25 is of the usual construction and is believed to require no detailed description, the same, however, being provided with the pointer 26 and the drum or its equivalent 27, around 55 which passes the endless connection or wires 28, the latter passing upwardly over the sheave 29, thence in practice horizontally and thence under the sheave 30, which is secured in any convenient fixed relation below the bridge 31, said wires 28 passing thence over the drum 32 of the stand 33, the latter being provided with the operating lever 34 of the usual construction, it being understood that the sheaves 29 and 30 are 60 mounted in fixed or stationary bearings and 65

that the stand 33 and the receiver 25 and their adjuncts may be of any usual or conventional type.

The operation is as follows:—

It will be understood that the stand 33 70 is in connection with the receiver 25, which is fastened to the front or sliding plate 1, by means of the endless connections or wires 28 and that any predetermined or desired tension on the wires 28 of the whole system can be obtained by the proper manipulation of the nuts hereinbefore referred to. 75

In case, for any reason, the distance between the telegraph stand 33 on the bridge 80 31 and the receiver 25 in the engine room should change, due to the expansion or movement of the vessel, it will be seen that my novel take-up device will compensate for any such expansion or movement through 85 the springs 20 and the sliding plate 1, having the telegraph receiver 25 thereon, and thus keep a constant tension on the whole system particularly on the wires 28, by merely adjusting when necessary the tension of the springs 20, which is desirable and necessary for a correct operation of the instruments, as will be evident to those skilled in 90 the art.

It will be apparent that by reason of the tension of the springs 20, the front sliding 95 plate 1 will be permitted to rise or to be lowered, whenever for any reason the distance between the telegraph stand 33 and the telegraph receiver 25 changes, so that the same tension will be at all times maintained 100 throughout the whole system.

It will be apparent that my novel device can be cheaply manufactured and readily installed in position in the engine room, and when once installed is not liable to get out 105 of order, and whenever it is desired to make the necessary adjustment of the tension of the springs 20, the same can be quickly and expeditiously done by the proper manipulation of the nuts on the rods 12. 110

I have deemed it unnecessary to show or describe in greater detail the construction of the stand 33 and the telegraph receiver 25, since this device may be of any usual or conventional type, my invention relating 115 particularly to the tension and take-up devices hereinbefore referred to.

It will be understood that in practice the endless connection 28 usually extends horizontally between the station-sheaves 29 and 30,—instead of being inclined, as shown in the diagrammatic view in Fig. 4. It will be further understood that slight changes may be made in the manner of collocating the various elements, which will come within the 120 scope of my invention.

It will now be apparent that I have devised a novel and useful construction of a take-up device for engine room telegraphs, which embodies the features of advantage 125 130

enumerated as desirable in the statement of the invention and the above description, and while I have in the present instance, shown and described a preferred embodiment there-
5 of which will give in practice satisfactory and reliable results, it is to be understood that the same is susceptible of modification in various particulars without departing from the spirit or scope of the invention or
10 sacrificing any of its advantages.

Having thus described my invention what I claim as new and desire to secure by Letters Patent is:—

1. In a take-up device for engine room 15 telegraph systems, a stationary back or guide plate, a front sliding plate supported thereon, abutments projecting from the upper portions of said plates, an engine room telegraph receiver secured to said front plate, 20 and tension devices intermediate said abutments carried by said front plate and back plate.

2. In a take-up device for engine room telegraph systems, a stationary back plate, 25 a front plate slidably mounted on said back plate, abutments carried on the upper front portions of said plates, springs intermediate of said abutments, and means for adjusting the tension of said springs and for retaining 30 the tension of said springs in their adjusted condition.

3. In a take-up device for engine room telegraph systems, a stationary back plate, a 35 front plate slidably mounted on said back plate, abutments carried on the fronts of said plates, and springs intermediate of said abutments, in combination with guide rods passing through said springs and the lower of said abutments, and means for adjusting 40 the tension of said springs.

4. In a take-up device for engine room telegraph systems, a back guide plate secured in fixed position, a front sliding plate capable of vertical movement wth respect 45 thereto, an engine room telegraph receiver fastened to said front plate, brackets secured to the upper portions of said front and back plates, rods secured in fixed position upon the upper brackets attached to said back 50 plate and having their lower ends projecting through and guided in the lower brackets

carried by said front plate, nuts on the intermediate portions of said rods, and tension devices between said nuts and said lower brackets.

55

5. In a take-up device for engine room telegraph systems, a stationary back plate, a front plate slidably mounted thereupon, an engine room telegraph receiver mounted on the lower portion of said front plate, 60 abutments secured to the tops of said plates, rods having their upper ends secured to the upper of said abutments and their lower ends passing freely through the lower of said abutments, coiled springs surrounding 65 said rods and having their lower ends supported on said lower abutments, and nuts carried by said rods above said springs for adjusting the tension of the latter.

6. In a take-up device for engine room 70 telegraph systems, a fixed back plate, a front plate slidably mounted thereon, abutments on said back plate, rods depending from said abutments, a telegraph receiver on the lower portion of said front plate, abutments on said front plate, springs surrounding 75 said rods and having their lower ends supported upon the abutments attached to said front plate, nuts and washers on said rods intermediate of their ends for varying 80 the tension of said springs, a stand on the bridge of the vessel, and an endless connection from said stand to said receiver.

7. The combination of a telegraph receiver adapted to be located in the engine 85 room of a vessel, a stand adapted to be located upon the bridge of said vessel, an endless connection intermediate of said stand and telegraph receiver, a fixed plate located in said engine room, a plate slidably supported upon said fixed plate upon which said telegraph receiver is mounted, abutments projecting from said plates, tension devices located intermediate said abutments and adapted to cushion the movement of said plate, and means for adjusting 90 the tension of said tension devices.

FRANK JOSEPH DAVIS.

Copies of this patent may be obtained for five cents each, by addressing the "Commissioner of Patents,
Washington, D. C."

It is hereby certified that the State of incorporation of the assignee in Letters Patent No. 1,307,727, granted June 24, 1919, upon the application of Frank Joseph Davis, of San Francisco, California, for an improvement in "Take-Up Devices for Engine-Room Telegraphs," was erroneously given as "Pennsylvania," whereas said State should have been given as *Delaware*, as shown by the record of assignments in this office; and that the said Letters Patent should be read with this correction therein that the same may conform to the record of the case in the Patent Office.

Signed and sealed this 15th day of July, A. D., 1919.

[SEAL.]

R. F. WHITEHEAD,

Acting Commissioner of Patents.
